UNITED STATES PATENT OFFICE.

WILLIAM HESS, OF BUFFALO, NEW YORK.

DESIGN FOR A RAIL OR SPINDLE FOR BEDSTEADS.

SPECIFICATION forming part of Design No. 27,107, dated May 25, 1897.

Application filed March 5, 1897. Serial No. 626,138. Term of patent 14 years.

To all whom it may concern:

Be it known that I, WILLIAM HESS, a citizen of the United States, residing at Buffalo, in the county of Erie and State of New York, have invented and produced a new and original Design for Rails or Spindles to be Used in the Manufacture of Metallic Bedsteads, of which the following is a specification, reference being had to the accompanying drawings, showing a part thereof.

Figure 1 is a face view of a solid rail or spindle containing my design, and Fig. 2 is a side view of the same.

The leading feature of my design consists of a solid rail or spindle in the shape of two separate yet connected scrolls, both said scrolls being on the same side of their said rail and substantially on the same plane, the inner end of each separate scroll being produced at any desired angle to an imaginary line drawn from center to center of the scrolls in rear of and contiguous to the outer circular parts of each scroll and beyond thereof on the same plane for connection to posts or rails of metallic bedsteads.

A is the rail or spindle, the connected scrolls being a continuation thereof, and both scrolls essentially curving inward toward each other and essentially to the same particular side of the said rail A, both scrolls being identical in 30 contour and on the same plane and identical in their formation and in their relation to their rail A.

The scrolls commence to curve at the part indicated by B and continuing upward and 35 toward each other in smaller circularity to the part denoted by C, continuing in smaller circular and curved form and then outward in rear of and contiguous to the said circular parts of the scroll and beyond the outer part 40 thereof, as indicated by D, for connecting purposes.

What I claim is—

The design for a solid spindle or rail for bedsteads as herein described and set forth. 45

WILLIAM HESS.
